UNITED STATES PATENT OFFICE.

HUGH MACINNES, OF JERSEY CITY, NEW JERSEY.

FLEXIBLE SHINGLE.

Application filed April 21, 1921. Serial No. 463,195.

To all whom it may concern:

Be it known that I, HUGH MACINNES, a citizen of the United States, residing at Jersey City, county of Hudson, State of New Jersey, have invented a certain new and useful Flexible Shingle, of which the following is a specification.

This invention is a weatherproof covering for roofs, walls, and other surfaces of houses, buildings, and other structures, and it pertains, more particularly, to a flexible shingle adapted for roofing purposes.

The shingle of this invention is of such physical form as to secure several functions important in this art, among which are facility of installation upon the surface to be covered; to retain each shingle and all parts thereof in interlocked relation to underlying shingles whereby the edge portions, and particularly the lower exposed corner, of each shingle are precluded from upward displacement by wind pressure so that the shingle lies flat upon the surface and excludes rain, snow and sleet from the marginal portions; and to impart to the exposed corner of the shingle the appearance of a thickened butt or end, the latter possessing the mechanical utility of facilitating the assemblage and interlocking of the shingles at the time of installation.

The shingle is composed of flexible material possessing the requisite waterproof and weatherproof qualities. Among the features of novelty are a bent under corner flap offset by an intervening shoulder, said flap being spaced for an appreciable distance relatively to the body of the shingle and said shoulder presenting to the eye of an observer a thickened butt or end for the shingle; further, in the provision of shoulders formed by notches in the opposite marginal portions of the shingle and extending inwardly with respect thereto, said notches and shoulders being each positioned intermediate two corners of the shingle and each notch being adapted for receiving the edge portion of an overlying shingle at a point adjacent the bent under flap; further, in the provision of tapering notches the edges of which are relatively inclined with a view to imparting a taper to the notch, which tapering form of notch permits the assemblage and interlocking of the shingles in a more facile manner.

Other functions and advantages of the invention will appear from the following de-

scription taken in connection with the drawings, wherein—

Figure 1 is a plan view of a flexible shingle embodying the invention.

Figure 2 is an elevation looking at one side edge thereof.

Figure 3 is an elevation showing two of the shingles laid against a roof or other surface.

Figure 4 is a view similar to Figure 3 with courses of shingles assembled inlapping order and illustrating the interlock of the overlying shingles with the underlying shingles.

Figure 5 is a view looking upwardly from the lower edge of Figure 4, illustrating the thickened butts of the shingles.

Figure 6 is a detail cross section on the line 6—6 of Figure 4.

Figure 7 is a plan view of the preferred form of shingle, and

Figure 8 illustrates the assemblage in courses of shingles like Figure 7.

The shingle A is composed of flexible material treated in a manner now well known in the art to render said material weatherproof and waterproof; in other words, the shingle is a blank composed of flexible roofing material impregnated or saturated with a waterproofing material, such as asphaltum, or other substance or substances the action of which is to impart to the resulting shingle the desirable weatherproof and waterproof qualities.

The shingle is of a desirable shape and size; but preferably the shingle is rectangular or diamond shape, it being essential in this invention that one corner portion be folded or doubled upon the shingle body to produce an underlying flap B.

A peculiarity of this part of the shingle is that the flap occupies a permanent or fixed relation to the shingle body, in contradistinction to a bendable relation thereto as in some devices which have preceded my invention; and, further, there is provided a shoulder C intermediate the flap and the shingle body, which shoulder serves the functions (a) of means for spacing the flap relatively to the shingle body so that a space of appreciable width intervenes the surface of the flap B and the surface of the shingle body (see Figure 2), and (b) the shoulder imparts to the shingle, when looking at the lower edge corner thereof, the appearance of

a thickened butt, see Figure 5, the apparent visible thickness of which is greatly in excess of the thickness of the layer of material composing the shingle. As shown, the 5 shoulder C is at a right angle to the plane of the shingle body and the plane of the flap, presenting a relatively wide edge at the thickened butt, but obviously this shoulder may be curved in cross section instead of 10 the straight cross section depicted in Figure 2. As shown, the underlying flap is free from contact with the surface of the shingle body, there being a space of appreciable thickness intermediate the opposing surfaces 15 of the shingle body and said flap. The separation or spacing of the flap with respect to the shingle body is advantageous in installing the shingles for the reason, among others, that the edge or margin of an 20 underlying shingle can easily be introduced into the space intervening the shingle body and the flap without requiring a relative displacement of flap to shingle or the application of pressure to force the shingle into 25 the desired interlocking relation.

The body portion of the shingle is provided with shoulders a, b for abutting contact with these portions of overlying shingle adjacent the bent under flaps thereof. As 30 shown in Figure 1, the shoulders a, b are formed by the provision of notches a', b' in the opposite side edge or marginal portions of the shingle, said notches extending inwardly from the edges and said notches being located near to the cut off corners c, c 35 of the shingle.

The operations of assembling and interlocking the shingles are shown in Figures 3 and 4. A course of shingles A is laid flat 40 upon the roof or other surface, with the cut off corners c of adjacent shingles in abutting relation, with the notched margins a', b' free from contact, and with the flaps B lying beneath the shingles and in contact with 45 the surface, (it being preferred to mechanically fasten the shingles individually by driving one or more nails through each shingle, it being necessary to use at least one nail driven through the underlying flap B of 50 each shingle. It is preferable to mechanically fasten each shingle by using three nails, one of which is driven through the flap B, as indicated at x in Figs. 1, 3, 4, 7, and 8, whereas two other nails, indicated at x¹, x², 55 are driven through the shingle approximately four (4) inches above a diagonal line extending between opposite corners and above the notches b, b¹, in Figs. 1, 3, and 4, or e, e¹, in Figs. 7 and 8. The nails to be 60 driven at x¹, x², should be about one inch from the outside edge of the shingle, and should not penetrate the underlying shingle, but the position of the nails x¹, x², in the underlying shingle should be such that said 65 nails x¹, x², are covered by the marginal por-

tions of the overlying shingles, whereas nail x is covered by the body of the shingle through the flap B of which said nail x is driven, as a result of which all the nails x, x¹, x², are covered by the shingles and hence 70 said nails are protected from the weather. The next course of shingles are positioned to overlap the shingles of the underlying layer or course, and so on in each succeeding course; but in applying each overlying 75 shingle the notched edges of two adjacent underlying shingles are interlocked with one of the overlying shingles as depicted in Figure 4, from which it appears that the margin of the flap together with the edge of the 80 shoulder C of said overlying shingle is received or fitted within one notch of an underlying shingle, it being apparent that the notches a', b' in two adjacent underlying shingles will receive the opposite end edges 85 of the shoulder C of the shingle immediately overlying said two adjacent shingles. When assembling the shingles the flap B of the overlying shingle extends beneath those portions of the two adjacent shingles next to 90 the cut off abutting corners c, c thereof, whereas the end portions of the shoulder C in the overlying shingle extends into the notches a', b' until contact is established with the shoulders a, b, the latter thus acting 95 as stops to the entry of shoulder C of the overlying shingle into said notches a', b' of the two underlying shingles.

The provision of the space intermediate the flap and the shingle body is an advantage 100 for the reason that the notched edges of the underlying shingles can easily enter said space without requiring the workman to lift the shingle or to devote time and labor to the manipulation of the same, and in addition to facilitating the operation of laying the shingles, said shoulder C presents to the eye the appearance of a thickened butt, see Figure 5, the depth of which butt end of the shingle is in excess of the thickness of the 105 individual plies or layers of material comprising the shingle body and the underlying flap.

It will be noted that in my invention the 110 notched shingle having the shoulder and the flap is adapted for direct interlocking engagement with other adjacent shingles by assembling the shingles for the shouldered end portion to be received directly into the notches of other shingles. This direct interlocking of the shingles enables me to dispense with metallic or other devices provided ordinarily on shingles of this class for effecting an interlock between the shingles, and by thus dispensing with the metallic 115 fasteners for interlocking the shingles I am enabled to materially simplify the construction and attain a desirable economy in manufacture, and in addition thereto effect a 120 decrease in the time and labor of the work- 125

man when engaged in the installation of the shingles.

A preferred embodiment of the invention is shown in Figures 7 and 8, wherein the 5 shingle A' is provided with the bent under flap B' producing the shoulder C', all as hereinbefore described. The corners are cut away at e', e', and notches e, e are provided to produce the shoulders e', each notch 10 being formed by edges e² which are inclined relatively to each other, the edges e² converging inwardly with respect to the margin of the shingle. The converging edges result in the formation of a tapering notch, 15 the taper of which enables the edge of shoulder C' on an overlying shingle to be fitted more easily and freely into said notch.

Having thus fully described the invention, what I claim as new and desire to secure by 20 Letters Patent is:

1. A shingle provided in a marginal portion with an inwardly extending notch and having at one corner a flap spaced relatively to the shingle body and producing a shoulder adapted for interlocking engagement 25 with the notch of an underlying shingle.

2. A shingle provided in two marginal portions with inwardly extending notches and having at one corner thereof an underlying flap producing a shoulder adapted 30 for interlocking engagement with notches of underlying shingles to effect a direct interlocking connection therewith.

3. A shingle provided at a marginal portion with an inwardly extended notch and having at one corner a flap spaced relatively to the shingle body and producing an offset, a shoulder directly engageable with the 35 notch of an underlying shingle to effect a positive direct interlocking connection therewith.

4. A shingle composed of composition roofing material and provided in two edges thereof with inwardly extending notches 40 and having at one corner an underlying flap

joined to the body of the shingle by a shoulder, the latter being adapted to be received in the notches of underlying shingles for effecting a direct interlocking engagement between said shingles.

5. A shingle composed of flexible material and provided in two opposite edges thereof with tapering notches, said shingle having a doubled under flap producing a shoulder adapted to be received in the notches of underlying shingles. 50

6. A shingle composed of flexible material and provided with notches in two of the margins and with a bent under flap producing a shoulder, the opposite corners of the shingle adjacent said notches being cut off. 60

7. A flexible shingle provided in two margins thereof with inwardly extending notches and having a bent under flap spaced relatively to the body of the shingle, said 65 flap producing an abrupt shoulder adapted to be received within the notches of underlying shingles for effecting a direct interlocking engagement between said shingles.

8. A shingle having opposite corners cut 70 away, and provided at one corner with an underlying flap and provided adjacent the cut away corners with notches, said underlying flap producing a shoulder for interlocking engagement with a notch in an underlying shingle. 75

9. A shingle provided at a marginal portion with an inwardly extended notch and having at one corner a shoulder directly engageable with the notch of an underlying shingle to effect a positive direct interlocking connection therewith, the depth of the shoulder exceeding the thickness of the body portion of the shingle, whereby said shoulder presents the appearance of a thickened 80 butt to the shingle. 85

In testimony whereof I have hereto signed my name this 18th day of April, 1921.

HUGH MacINNES.
